UNITED STATES PATENT OFFICE.

GEORGE A. KERESTES, OF PITTSBURGH, PENNSYLVANIA.

MOVING-PICTURE TARGET APPARATUS.

1,189,135.

Specification of Letters Patent. Patented June 27, 1916.

Application filed March 2, 1914. Serial No. 821,879.

To all whom it may concern:

Be it known that I, GEORGE A. KERESTES, a citizen of the United States, residing at Pittsburgh, in the county of Allegheny and 5 State of Pennsylvania, have invented certain new and useful Improvements in Moving-Picture Target Apparatus, of which the following is a specification.

The object of this invention is to provide 10 means for controlling target apparatus used in connection with cinematographs in which a moving picture is projected upon a perforable screen, in the rear of which is a source of illumination, so that that portion 15 of the screen pierced by a projectile will be indicated by the light shining through.

It is desirable that the moment the projectile pierces the target the machine for projecting the picture be stopped so that 20 the proper relative positions of the object at which the marksman aims and the pierced part of the screen be truly disclosed. I have provided means in connection with a fire-arm whereby the stopping of the projecting machine will be accomplished by 25 means controlled by the movement of the hammer, and I have further provided means whereby the hammer can be cocked or drawn back ready for firing without in 30 any way affecting the controlling apparatus, the controlling being accomplished by the cartridge exploding movement of the hammer.

In the drawings: Figure 1 is a diagrammatic view of a picture projecting apparatus, a target with its screens and light source, the circuits for controlling the target screens and the picture projecting apparatus; Fig. 2 is a view partly in section 35 and partly in elevation of a clutch mechanism useful in connection with the projecting apparatus, the specific form of clutch forming part of an application previously filed by me; Fig. 3 is a longitudinal 40 sectional view through a gun stock to which the circuit breaker included in my invention is applied; Fig. 4 is an enlarged elevational view of the circuit breaker in the position the parts will assume when the 45 hammer is down on the firing pin; Fig. 5 is a similar view showing the moving contact of the circuit breaker moving into operating position; Fig. 6 is a similar view showing the movable contact ready to operate, and the position which it will assume 50

when the hammer is drawn back ready to fire; Fig. 7 is a top view of the circuit breaker; Fig. 8 is a sectional view on the line 8—8 of Fig. 4; Fig. 9 is a sectional view on the line 9—9 of Fig. 6; and Fig. 60 10 is an end view of the gun stock with the guard plate removed.

The driven shaft 1 of the moving picture machine 2 carries a clutch member 3 fast to the shaft, and it is provided with a 65 toothed face 4 adapted to engage a similar face 5 on the complementary clutch member 6 loose on the shaft 1, and which may or may not be a part of the drive pulley 7 to which it is secured.

Interposed between an abutment or shoulder 8 on the shaft 1 and the pulley 7 is a 70 spring 9 coiled around the shaft 1, the tendency of which is to maintain the members 3 and 6 in clutched engagement. The 75 clutch member 3 is provided with a plurality of radial recesses 10 corresponding in number with the number of vibrations of the shutter per second (in the present instance there are sixteen).

One face of the clutch member 6 is provided with a spiral groove 11. The clutch actuator is shown as consisting of the levers 12 and 13 pivoted at their lower ends to suitable supports 14 and 15 and at their 80 upper ends to the levers 16 and 17 which are secured to a pivot pin 18, the parts being suitably supported, Fig. 1 indicating one form in which this support may be provided. On the lever 13 is a recess engaging finger 19 to engage in the recesses 10 in member 3. Anti-friction devices 20 are carried by the levers to engage the spiral groove 11 on the clutch member 6. The 85 clutch actuator is provided with a link 21 connected to an operating lever 22, pivoted at 23, and connected to the core 24 of the solenoid 25. The solenoid 25 is connected to the main line wires 26 and 27 of a suitable source of supply through the medium 100 of the wires 28 and 29, said circuits being adapted to be broken, however, by the bridge contact 30 moving out of engagement with the spring contacts 31 and 32. The bridge contact 30 may be moved into 105 closing position by a solenoid 33, the core of which is connected to said bridge contact 30 and the circuit for which consists of the conductors 34 and 35 receiving electric current from a storage battery 36.

- The circuit for the solenoid 33 may be controlled by suitable mechanism within or on the fire-arm, and which will be more specifically described hereinafter. The circuit consisting of the wires 28 and 29 may be broken by the solenoid 37 connected to the bridge contact 30 by a flexible connection 38, the circuit for the solenoid 37 being here shown as consisting of the conductors 39 and 40 supplied with energy by a battery 41. On the core 24 of the solenoid 25 is a member 42 adapted to close the circuit between contacts 43 and 43^a while the solenoid 25 is energized.
- 44 is a contact on the operating lever 22 which, when the core 24 is being moved inward by the energizing of solenoid 25, will move past the insulation 45, but which on the return movement will contact with a contact 46 so as to close the circuit consisting of the wires 47 and 48 one of which is connected to the main line and which operates a solenoid 49 connected to a pawl 50 engaging ratchet 51 on the rotating shaft 52 around which the outer screen 53 passes, the inner screen 54 being driven from the shaft 52 at a different speed from the outer screen. It will be apparent that when motion is imparted to the shaft 52 any holes in the two screens which are in register will be staggered so that the light from the box 55 of the target will be excluded.
- 56 is a spring connected to the pawl 50 and opposed to the solenoid 49.
- 35 It will be apparent that if the circuit consisting of the wires 34 and 35 is closed that the solenoid 33 will be energized. That the energization of the circuit consisting of the wires 34 and 35 will be effective in causing the bridge contact 30 to close the circuit consisting of the wires 28 and 29, so as to cause the operating lever 22 to force the lever 13 with its finger between the two clutch devices and throw the clutch finger 19 into the recess 10 so as to prevent the shaft 1 of the machine from rotating. The movement of the anti-friction members across the face of the member 6 will force the clutch teeth members 4 and 5 out of engagement, whereby the member 3 will be held rigid by finger 19, but member 6 will continue to rotate, however, inasmuch as it is loose on the shaft. Its continued rotation causes the anti-friction devices to subsequently move the finger 19 out of engagement with the recess 10 which it engages.
- When the levers have been thrown into engagement with the recesses 10, the circuit consisting of the wires 39 and 40 will have been closed so that the solenoid 37 will be energized, and as soon as it is, the circuit consisting of the wires 28 and 29 will be broken, because the flexible connection 38 attached to the contact 30 will cause the contact 30 to move away from the contacts

31 and 32, and as soon as this takes place, the solenoid 25 will cease to be energized, and as the lever 22 is moved out by the lever 13 riding on the spiral groove of the clutch member 6, the contact 44 will wipe the contact 46, momentarily closing the circuit consisting of the wires 47 and 48 so as to energize the solenoid 49. The movement imparted to the core of the solenoid is sufficient to impart a rotary movement to the roller 52 so as to move the outer screen 53 and thereby stagger the perforations in the screens 53 and 54 as previously described. As will be readily understood, this general arrangement provides a timing element in the operation. While solenoid 33 is momentarily energized when the hammer drops on to the cartridge, solenoid 37 breaking the circuit of solenoid 25 as soon as core 24 reaches its inward position, and thus retaining the various circuits active momentarily, the period of time during which the screens remain stationary and the effect of a shot ascertained is controlled by the mechanical means shown in Fig. 2, the latter controlling the length of time during which the cinematograph remains stationary, and the screens held from their relative movements. Consequently, the timing element is mechanical in operation, being brought into activity through electrical means and in turn acting to shift the screens as presently described. The initial circuit, of course, is that consisting of the wires 34 and 35 with its battery 36. The closing of this circuit sets all the other circuits in operation in their proper order, so I have provided means controllable by a fire-arm which will momentarily close the primary circuit so that the mechanisms controlled by the remaining circuits will be set in operation and so that the act of stopping the picture machine will be coincident with the discharge of the fire-arm. The mechanism for effecting the closing of the circuit is illustrated in detail in Figs. 4 to 10 both inclusive.

Referring now more particularly to Figs. 3 and 10, 56 designates the stock of the fire-arm, in the present instance a rifle, between the heel and toe of which is a recess 57 covered by the guard plate 58. In the recess 57 is a plate 59 receiving the wire 35 which enters through the channel 60 in the gun stock, and the plate 61 receives the wire 34 through the same channel 60. From the plates 59 and 61, the wires 34 and 35 continue to the lock case through the longitudinal channel 62. The lock case 63 contains the usual operating mechanism for the hammer 64, its trigger 65 and the operating spring 66, these all being of any approved construction. Within the lock case, I provide a mechanism supporting block 67 which may consist of pressed fiber or other suitable insulating material. The block 67 is substan-

tially rectangular except that one corner is cut away to provide for the movement of the hammer operating spring 66, and the block is provided with a cut out portion or 5 recess 68 in which the fixed contacts and movable contact are located. Pivoted to one side of the block 67 is a substantially rectangular plate 69 of good electrical conductivity, said plate being pivoted to the 10 block 67 at 70, and provided with an elongated recess 71 through which a pin 72 from the block 67 projects. The plate 69 carries a segmental contact block 73 having a contact face 74 of conducting material which 15 is connected to the plate 69, the block 73 being of suitable insulating material. The contact face 74 is inclined but substantially parallel with the spring contact 75 which is complementary to the contact 74. That is to 20 say, the members 74 and 75 constitute what might properly be termed a split contact because the conductor wire 34 is split adjacent to the block 67 and one branch 34' is connected to the pin 70 so that current can 25 be conducted through it to the plate 69, and the other split portion 34'' is connected to the binding post 76 of the contact 75. The wire 35 is connected to a binding post 77 carrying a swinging link 78 provided with 30 an elongated slot 79 in which is slidably secured the movable contact pin 80 connected to a movable part of the fire-arm, in the present instance the hammer 64, by the actuating link 81. 83 is a flat spring connected 35 to the block 67 by the fastening device 83', said spring being positioned adjacent to the end of the block 73 so that the return movement of the movable contact 80 will be retarded as will be explained hereinafter.

40 Assuming all the parts to be properly assembled, and the hammer down on the firing pin, the parts will be in the position shown in Fig. 4. When the operator cocks the hammer, that is, pulls it back toward 45 the butt of the gun, the link 81 will move the movable contact 80 in the slot 84, as shown in Fig. 5, until the hammer is drawn back its fullest extent, when the contact 80 will be in the recess 85 of the slot 84. Al-

50 though the contact pin 80 moves under the block 73 so as to raise the block and the plate 69 which carries it, the circuit consisting of the wires 34 and 35 will not be closed because the sides of the block 67 are of insulating material as well as the block 73, and the pin 80 is of less length than the thickness of the block 67, so the pin 80 will not come in contact with the plate 69 or any other conducting element. When the contact pin 81 is in the recess 85 of the slot, the fire-arm is ready to be fired, and as the plate 69 is a gravitated plate, the pin 80 will have moved under the block 73 raising it, as shown in Fig. 5, the plate dropping back when the pin has passed block 73 and rests

in the recess 85, the position shown in Fig. 6 or in its original position as shown in Fig. 4. When the hammer moves forward, it carries the pin 80 with it, and inasmuch as the plate 67 and the block 73 have assumed the position shown in Figs. 4 and 6, it is obvious that the pin must be guided between the contacts 74 and 75 assuming, as it passes between the contacts 74 and 75, the position shown in dotted lines in Fig. 6. 75 There will be a momentary contact between pin 80 and contacts 74 and 75 because the spring 66 will be strong enough to drive the hammer down on the firing pin instantaneously. The momentary contact, however, 80 will enable the current to flow from the battery 36 through conductor 34, solenoid 33, branch 34', pin 70, plate 69, to contact 74, and through branch 34'' to contact 75, returning to battery 36 through contact 80 85 and lead 35.

The movement of the contact 80 from the contacts 74 and 75 will cause the contact 80 to strike the spring 83 which will cause it to rebound and be guided into the slot 84 so 90 that it assumes the position shown in Fig. 4 ready to be moved down through the slot 84 into the recess 85 and in position to again close the circuit as has been previously explained. The instantaneous closing of the 95 circuit coincident with the movement of the hammer will instantaneously energize solenoid 33 causing the solenoid 25 to be energized, which will in turn cause solenoid 37 to be energized to break the primary circuit. 100 As the picture machine is stopped, the operation of the solenoids 33, 25 and 37 follow in such rapid sequence as to be almost instantaneous, indeed the operation of the solenoids 33 and 25 and the retarding mechanism for the moving picture machine being to all intents and purposes so absolutely instantaneous that the picture projected on the screen at the time the projectile passes therethrough will remain during such time that 105 the machine is stopped, so that the actual position of the picture at the time the projectile pierced the screen can be observed by the marksman.

110 From the foregoing description, it will be seen that the projecting machine is under the control of the marksman, and that the hammer on the fire-arm and that the movement of the hammer toward the firing pin will be effective in actuating mechanism 115 which will cause the projecting machine to cease operating. In its broad aspect, the circuit closer may be used in other connections than herein shown.

120 What I claim is:—

1. In mechanism of the character described, the combination with the hammer of a fire-arm, of a circuit make and break mechanism controlled by movements of the hammer, said mechanism including contacts 125

- normally breaking the circuit, means operatively connecting said hammer and one of said contacts, said means being responsive to the movements of the hammer for moving said contact in a cycle, the movements of said contact in one direction of movement of the hammer closing the circuit, said contact operating to maintain the circuit broken during a movement of the hammer in the opposite direction.
10. 2. In mechanism of the character described, the combination with the hammer of a fire-arm, of a circuit make and break mechanism controlled by movements of the hammer, said mechanism including contacts normally breaking the circuit, means operatively connecting said hammer and one of said contacts, said means being responsive to the movements of the hammer for moving said contact in a cycle, the movements of said contact in one direction of movement of the hammer closing the circuit by a wiping action, said contact operating to maintain the circuit broken during a movement of the hammer in the opposite direction.
15. 3. A firearm having a hammer, a circuit closer, a movable contact, a split contact, said contacts being located in the lock case of the firearm, and means connecting the hammer and movable contact to cause the movable contact to move into momentary closing position between the complementary members of the split contact when the hammer moves into cartridge exploding position.
20. 4. In mechanism of the character described, the combination with the hammer of a fire-arm, of a circuit make and break mechanism controlled by movements of the hammer, said mechanism including contacts normally breaking the circuit, means operatively connecting said hammer and one of said contacts, said means being responsive to the movements of the hammer for moving said contact in a cycle, and means coöperating with said moving contact for controlling the cycle movements of the contact, said control restricting circuit closing action to the period of travel of the hammer in one direction, said control preventing the circuit closing action during the remainder of the contact cycle.
25. 5. In a circuit closer picture machine, the combination with a firearm having a hammer, of a block in rear of the hammer, a yielding contact on said block, a movable contact carried by the block and movable past the yielding contact, and a link connected to the movable contact and to the hammer.
30. 6. A circuit closer comprising a block, a spring contact finger carried by the block, a swinging movable contact, a firearm having a hammer, and an operating link connected to the swinging contact and the hammer.
35. 7. A circuit closer comprising a block, a spring contact finger carried by the block, a swinging movable contact, and an operating

link connected to the swinging contact and having means for attachment to a movable part of a fire-arm.

8. A circuit closer comprising a yielding contact, a link, a contact carried by the link and slideable in a slot in said link, and means for sliding the second mentioned contact in the slot to contact with the first mentioned contact.

9. In a circuit closer, a yielding contact, a swinging plate, a contact carried by the swinging plate, and a bridging contact movable between the two first named contacts.

10. In a circuit closer, a block, a spring contact carried by said block, a plate, an insulating block carried by the plate and within an opening in the first named block, means for permitting movement of the plate, a contact on one edge of the second mentioned block, a contact adjacent thereto, a swinging contact, and means for moving the swinging contact within the opening in the first named block, first between the insulated edges of the two blocks and then between the contact edge of the second mentioned block and the spring contact.

11. In mechanism of the character described, the combination with the hammer of a fire-arm, of a circuit make and break mechanism controlled by movements of the hammer, said mechanism including contacts normally breaking the circuit, means operatively connecting said hammer and one of said contacts, said means being responsive to the movements of the hammer for moving said contact in a cycle, and means coöperating with said moving contact for controlling the cycle movements of the contact, said control restricting circuit closing action to the period of travel of the hammer in one direction, said control preventing the circuit closing action during the remainder of the contact cycle.

12. In mechanism of the character described, the combination with the hammer of a fire-arm, of a circuit make and break mechanism controlled by movements of the hammer, said mechanism including contacts normally breaking the circuit, means operatively connected with and responsive to the movements of the hammer for moving one of said contacts in a cycle, and a gravity element coöperating with said moving contact for controlling the cycle movements of the contact, said control restricting circuit closing action to the period of travel of the hammer in one direction.

13. In mechanism of the character described, the combination with the hammer of a fire-arm, of a circuit make and break mechanism controlled by movements of the hammer, said mechanism including contacts normally breaking the circuit, means operatively connecting said hammer and one of said contacts, said means being responsive

to the movements of the hammer for moving said contact in a cycle, and means coöperating with said moving contact for controlling the cycle movements of the contact, said control restricting circuit closing action to an intermediate portion of the period of travel of the hammer in one direction.

14. In target apparatus for use with cinematographs and the like and in combination, 10 a picture projecting device including drive connections, a mechanical time control operative to disengage the device from its drive during a predetermined period, a target screen on which the picture is projected, a fire-arm, and means responsive to the movements of the hammer of the fire-arm for automatically providing a cycle of operations including the following:—manipulating the time control to stop the movements of the projecting apparatus and to render the control active during a predetermined period, and resetting the control manipulating mechanism, and manipulating the screen to obliterate the projectile opening therein during the activity of the control mechanism, said time control including an element movable with the picture projecting device.

15. In a circuit closer for firearms, the 30 combination with a block provided with a recess, a pivoted contact within the recess, a spring contact normally bearing upon the pivoted contact, a contact movable between the pivoted contact and spring contact, and a swinging link connecting the last mentioned contact to the block.

16. In target apparatus for use with cine-

matographs and the like and in combination, a picture projecting device, a target screen on to which the picture is projected, 40 and means for arresting the movement of the device during a predetermined period and automatically continuing such movement upon the completion of said period, said means including a normally inactive electric circuit, means including a contact operatively connected with and responsive to the movements of the hammer of a fire-arm for rendering said circuit active, and mechanism controlled by said circuit and operative within and by the drive connections of said device during such predetermined period for effecting such arresting movements.

17. In target apparatus for use with cinematographs and the like and in combination, 45 a picture projecting device, a target screen on to which the picture is projected, and means for arresting the movement of the device during a predetermined period, 50 said means including a normally inactive electric circuit having an interruption controlled by movements of the hammer of a fire-arm, and mechanism controlled by said circuit and operative within the drive connections of said device for effecting such arresting movements, said mechanism being 55 variable at will to control the length of such arresting action.

In testimony whereof, I affix my signature in presence of two witnesses.

GEORGE A. KERESTES.
